UNITED STATES PATENT OFFICE.

PAUL C. HUGHES, OF TULSA, OKLAHOMA.

BURNER.

Application filed February 19, 1926. Serial No. 89,382.

This invention relates to an improvement in burners of the type forming the subject matter of my co-pending application, filed January 16, 1926, Serial #81,779.

5 One of the principal objects of the invention is to provide a burner which thoroughly commingles the gas or other fuel used and the air to produce a highly combustible mixture adapted to be burned to generate a maximum amount of heat with economy in the consumption of fuel and little or no deposit of carbon.

Another important object of the invention is to provide a burner having reversible 15 jets so constructed and organized as to produce either a laterally directed or an upwardly directed sheet of flame thereby making the burner readily adaptable for various types of boilers and to meet varying 20 conditions.

A further object is to provide a burner which is of simple and durable construction, reliable and efficient in operation, and easy and comparatively inexpensive to 25 manufacture.

Other objects and advantages reside in certain novel features of the construction, arrangement and combination of parts which will be hereinafter more fully 30 described, and particularly pointed out in the appended claims, reference being had to the accompanying drawing forming a part of this specification, and in which

Figure 1 is a perspective view showing a 35 burner constructed in accordance with the present invention and illustrating the jets thereof in a position to provide a horizontal sheet of flame,

Figure 2 is a sectional view illustrating 40 the construction of the burner and the mounting of the burner pipes, and

Figure 3 is a detail perspective view of one of the burner pipes.

Referring to the drawings, the numeral 45 1 designates generally a furnace or boiler in the firebox of which the burner constituting the present invention is placed. The burner is supported at the upper end of a casing or fuel supply pipe 2. The gas pipe 50 2 delivers the gas or fuel in through the bottom 3 with a gas chamber designated generally at 4, and having a body portion 5 of frusto-conical form. The gas chamber also has a top wall 6 which is provided with 55 an annular extension 7 from the outer edge of which a depending apron 8 of frusto-

conical form extends, the apron 8 being parallel to the body portion 5 of the gas chamber and terminating in the plane of the bottom of the chamber. As illustrated 60 in Figure 2, the outer wall of the body portion of the chamber 4 and the apron 8 contact to define an air chamber 9.

The body portion 5 of the gas chamber is provided with a circular series of openings 10 through which the gas issues in the form of jets. The apron 8 has openings 11 aligned with the openings 10, and as illustrated in Figure 2, both the openings 10 and 11 are preferably inclined upwardly. 70

In the openings 11 of the apron 8 burner pipes designated generally at 12 are mounted. The walls of the openings 11 are tapered as shown at 11^a, Figure 2, and the inner ends of the burner pipes are similarly 75 tapered as indicated at 12^a. This provides for the side joint between the burner pipes and the apron, and in order to enhance the mechanical connection between the burner pipes and the openings, and prevent turning movement of the burner pipes in their 80 openings, each burner pipe has oppositely extending lugs 13 engageable with grooves 14 in the apron 8 between the openings 11. Each burner pipe 12 has a body portion 15 85 which is straight and a discharge end 16 which extends from the body portion at an angle of substantially 45°. This angularly extending discharge end portion 16 has its outer end closed and has jet openings 17 at 90 each side of its outer end. When the burner pipes are positioned as shown in Figures 1 and 2, the flame which they generate is horizontally disposed in the furnace. However, by taking the burner pipes off 95 of the apron and turning them or reversing them, the discharge end portion 16 may be disposed to extend vertically whereby the burner pipes create a vertically extending sheet of flame in the furnace or boiler. 100

If desirable, the air supplied to the space 9 may be supplied through the ordinary dampers or through the ash pit, or if a forced draft is used, through an air supply duct 20, which is connected up with the lower 105 end of the apron 8.

I claim:—

1. A burner including a gas chamber having a body portion provided with discharge openings, said gas chamber having an extension at its upper end and an inclined 110 pendent apron carried by the extension and

overlying the body portion of the gas chamber and having openings alined with the discharge openings of the gas chamber, and burner pipes mounted in the openings of the 5 apron, said apron defining with the body portion an air space whereby the jets of gas issuing from the openings of the body portion entrain air and carry it into the burner pipes whereby a combustible mixture is produced, said burner pipes having their inner 10 ends tapered, the walls of the openings of the apron being correspondingly tapered, said burner pipes having oppositely disposed lugs, said apron having grooves coacting 15 with the lugs.

2. A burner including a gas chamber having a body portion provided with discharge openings, said gas chamber having an extension at its upper end and an inclined pendent 20 apron carried by the extension and overlying the body portion of the gas chamber and having openings alined with the discharge 25 openings of the gas chamber, and burner pipes mounted in the openings of the apron, said apron defining with the body portion an air space whereby the jets of gas issuing from the openings of the body portion en-

train air and carry it into the burner pipes whereby a combustible mixture is produced, said burner pipes having their outer ends 30 angularly disposed so as to extend horizontally in one position and vertically in another position.

3. A burner including a gas chamber having a body portion provided with discharge 35 openings, said gas chamber having an extension at its upper end and an inclined pendent apron carried by the extension and overlying the body portion of the gas chamber and having openings alined with the discharge 40 openings of the gas chamber, and burner pipes mounted in the openings of the apron, said apron defining with the body portion an air space whereby the jets of gas issuing from the openings of the body portion entrain air and carry it into the burner pipes whereby a combustible mixture is produced, said burner pipes having their outer ends 45 provided with discharge openings and also being angularly disposed so as to extend in different directions and different positions of the burner pipes.

PAUL C. HUGHES.
